ELECTRICAL CARRIER WAVE SIGNALING
SYSTEM

Frank Fairley, London, England, assignor to International Standard Electric Corporation, New York, N. Y.

Application May 21, 1941, Serial No. 394,457
In Great Britain October 24, 1940

4 Claims. (Cl. 178—44)

This invention relates to carrier wave signaling systems.

An object of the invention is to provide a single channel system which is intended to have a wider field of use than the known types of single channel systems hitherto used.

According to a feature of the invention, in a single channel carrier wave signaling system, transmission is effected over a transmission line from a first terminal station to a second terminal station on one modulated side-band of a carrier frequency and in the other direction on both modulated side-bands of the same carrier frequency, a source of carrier frequency waves being provided at the first terminal station only and means being provided thereat for selecting and demodulating only one of the received side bands.

According to another aspect of the invention in a carrier wave signaling system a first terminal station comprises a transmitting branch arranged to transmit one modulated side-band together with unmodulated carrier frequency waves and a receiving branch arranged to select and demodulate the other side-band of the same carrier frequency and a second terminal station comprises a single circuit which performs the double function of modulator and demodulator, the carrier frequency waves for modulation and demodulation at the second terminal station being supplied from the first terminal station.

According to a still further aspect of the invention a carrier wave signaling system is provided comprising first and second terminal stations connected by a transmission line and a third terminal station connected to a point in said transmission line intermediate said first and second terminal stations, said first and second terminal stations each being arranged to transmit one modulated side band and to receive and demodulate the other side band of the same carrier frequency, and said third terminal station comprising a single circuit adapted to transmit both modulated side-bands and to receive and demodulate either side-band transmitted from the first or second terminal station, the carrier frequency waves used for modulation or demodulation at the third terminal station being transmitted over the line from either one of the first or second terminal stations.

The above features of the invention will be better understood from the following description taken in conjunction with the accompanying

drawings, Figs. 1 and 2 of which are respectively schematic lay-out diagrams of the equipment at the two terminal stations of a system according to the invention whilst Fig. 3 is a layout diagram of a further system according to the invention.

Referring to Fig. 1, the terminal equipment there shown consists of the basic circuit used in a known type of single channel carrier system.

Considering the transmission on the carrier channel, speech from the switchboard is applied via the terminating set of hybrid coil TS to the modulator M, which is of the balanced type, in which the carrier is suppressed. One of the sidebands is selected by the band filter BF and applied to the transmitting amplifier TA from whence it passes via the directional filter TDF and high pass line filter HPL to the open wire or cable line L. In the receiving direction the sideband passes via the receiving directional filter RDF to the demodulator DM and the reproduced speech passes via the low pass filter LP and is amplified by the receiving amplifier RA for transmission to the switchboard via the 4-wire termination. The oscillator O supplies the carrier frequency both to the modulator and demodulator. A voice frequency circuit is provided via the low pass filter LPL. It may be arranged by switching that the directional filters TDF and RDF are interchanged in circuit position and that a second band filter passing the opposite sideband of the carrier frequency is connected in place of the original band filter, thus converting what may be termed an "A" terminal into a "B" terminal. The provision of such a switching arrangement avoids the necessity for having available two types of terminals for any emergency connection which it may be desired to install. This system, since it uses suppressed carrier and a directional transmission of frequencies, may be readily repeatered and extended to cover any large distances.

The output of the oscillator O is connected to the junction of filters TDF and RDF. The terminal shown in Fig. 1 will then transmit both the upper sideband of the carrier frequency and the carrier frequency itself. Such a terminal is used in conjunction with a terminal of the type shown in Fig. 2 which corresponds in its broad aspects with the inert terminal of a system as described in British specification No. 427,605, and requires no power supply for its operation. The upper sideband of the carrier frequency and carrier frequency itself applied to the inert terminal

pass via the line filter HPL to the modulator-demodulator M, which is an unbalanced type of modulator, and the reproduced speech passes via the low pass filter LP to the switchboard. For transmission in the other direction, speech from the switchboard passes via the low pass filter LP to the modulator-demodulator M, where it modulates the carrier frequency transmitted from the terminal of Fig. 1. Both sidebands pass via the high pass line filter HPL to the terminal of Fig. 1, in which the lower sideband only is received via the receiving directional filter RDF. The lower sideband then is demodulated in the ordinary way by the remainder of the equipment. Such a system will have the advantage of the system described in British specification No. 427,605 in that no power supply is required at the inert terminal, but will avoid the limitation of this system that the lowest overall transmission equivalent obtainable is that of the line at the carrier frequency, together with the basic losses of the two terminals. In this case, due to the use of one sideband in one direction and to the selection of the other sideband from the two sidebands sent in the other direction, it will be possible to obtain considerable gain at the Fig. 1 terminal without danger of "singing," and to make up for the attenuation of the open wire line at the carrier frequency.

According to a modified arrangement shown in Fig. 3, if two terminals are located at the two ends of a circuit, one being set to become the "A" terminal, i. e. to transmit the upper sideband of the carrier frequency and the other being set to become the "B" terminal, i. e. to transmit the lower sideband of the carrier frequency and if it is arranged that either but not both of these terminals is at the same time allowed to transmit the carrier frequency itself from the oscillator O to line, it is possible to connect in shunt on this circuit at an intermediate point an inert terminal of the Fig. 2 type and to operate the system using the Fig. 2 as an intermediate station. The "A" terminal will be similar to Fig. 1 whilst the "B" terminal will also be similar to Fig. 1 with the exception that the connection from the oscillator O to the junction of the filters TDF and RDF will be removed and the filter BF adjusted to pass only the lower side-band. The Fig. 2 terminal may receive the transmitted sideband from both the "A" or "B" terminal and at the same time still receive the transmitted carrier from the terminal "A" which is arranged to transmit this carrier and is thus able to demodulate either sideband at will. In the other direction, the Fig. 2 terminal generates both sidebands one of which is received by the "A" terminal and the other of which is received by the "B" terminal. Since it is possible to arrange that the carrier is transmitted from either of the terminals "A" or "B", it is convenient to arrange that the terminal transmitting the carrier is the nearest one to the Fig. 2 rather than that the more distant one should transmit the carrier. It will be appreciated that in order that the system may operate satisfactorily it is necessary that the terminal "B" which is not transmitting the carrier frequency must suppress the carrier received over the line from the distant terminal before demodulation. If there is any appreciable amount of carrier remaining at demodulation, lack of synchronism will cause the usual troubles associated with excessive carrier leak on suppressed

carrier systems. Normally the system will have sufficient suppression of the carrier frequency in the filter RDF for this purpose but in certain cases it may be preferable to arrange the filter RDF to pass a wider band of sideband frequencies and thus to provide insufficient suppression of the incoming carrier frequency in this filter to avoid demodulation troubles.

What is claimed is:

10. A single channel two-way carrier wave signaling system comprising a first terminal station, a second terminal station and a two-wire signal transmission line interconnecting said first and second terminal stations, a source of carrier frequency waves at said first terminal station only, means for transmitting one modulated side band of said carrier frequency from said first terminal station to said second terminal station over said transmission line, means for transmitting unmodulated carrier waves from said source over said transmission line to said second terminal station, means for transmitting both modulated side bands of said carrier frequency from said second terminal station to said first terminal station over said transmission line, and means at said first terminal station for selecting and demodulating only one of the side bands received thereat.
15. A single channel two-way carrier wave signaling system comprising a first terminal station, a second terminal station and a two-wire signal transmission line interconnecting said first and second terminal stations, said first station including a source of carrier frequency waves, a transmitting branch comprising means for transmitting one modulated side band of said carrier frequency and a receiving branch comprising means for demodulating the other side band of the same carrier frequency, and said second
20. terminal station comprising a single circuit which performs the double function of modulator and demodulator, and means at said first terminal station for transmitting unmodulated carrier waves from said source over said transmission line to said second terminal station for effecting modulation and demodulation thereat.
25. A two-way carrier wave signaling system comprising first and second terminal stations interconnected by a single two-wire signal transmission line, and a third terminal station connected to a point in said transmission line intermediate said first and second terminal stations, means at said first and second terminal stations to transmit one modulated side band and to receive and demodulate the other side band of the same carrier frequency, a single circuit at said third terminal station for transmitting both modulated side bands of the same carrier frequency and for receiving and demodulating the side bands transmitted from the first and second stations, and means at one of said first and second stations for transmitting carrier frequency waves over said transmission line to said third terminal station for effecting modulation and demodulation thereat.
30. A carrier wave signaling system according to claim 2 in which a modulator in said transmitting branch and a demodulator in said receiving branch at said first terminal station are supplied from said source of carrier waves, and an output of said source is also connected to said transmission line.

FRANK FAIRLEY.
